(57) **CLAIM**

The ornamental design for an ammunition can cover, as shown and described.

DESCRIPTION

FIG. 1 is a perspective view of the ammunition can cover.

FIG. 2 is a top plan view thereof.

FIG. 3 is a front elevational view thereof.

FIG. 4 is a rear elevational view thereof.

FIG. 5 is a left side elevational view thereof.

FIG. 6 is a right side elevational view thereof; and,

FIG. 7 is a bottom plan view thereof.

The broken lines in the figures represent stitching and are part of the claimed design.
